US00D703530S

(12) **United States Design Patent**
Caldecourt et al.

(10) **Patent No.:** US D703,530 S
(45) **Date of Patent:** ** Apr. 29, 2014

(54) **PACKAGING**

(75) Inventors: **Joshua Caldecourt**, Fort Collins, CO (US); **Ariana Schiff**, Fort Collins, CO (US)

(73) Assignee: **Otter Products, LLC**, Fort Collins, CO (US)

(**) Term: **14 Years**

(21) Appl. No.: **29/417,064**

(22) Filed: **Mar. 29, 2012**

(51) **LOC (10) Cl.** 09-03

(52) **U.S. Cl.**

USPC **D9/432**

(58) **Field of Classification Search**

USPC D9/414, 416, 418, 420-424, 430-433, D9/455-456; D3/272, 273, 302; 206/267, 206/269, 270, 273, 299, 737, 740, 822; 229/100, 101, 101.3, 106, 108-122

See application file for complete search history.

(57) **CLAIM**

The ornamental design for packaging, as shown and described.

DESCRIPTION

FIG. 1 is a front isometric view of packaging showing our new design;

FIG. 2 is a front view thereof;

FIG. 3 is a right view thereof; and,

FIG. 4 is a top view thereof.

The even broken lines depict unclaimed environment. The dot-dash lines represent boundaries of the claim. All broken lines form no part of the claimed design.

1 Claim, 4 Drawing Sheets

FIG. 1

FIG. 2

FIG. 3

FIG. 4
